REVERSE CONTROL MECHANISM

Otis F. Rodgers, Whiting, Iowa

Application September 26, 1933, Serial No. 691,052

2 Claims. (Cl. 188—30)

This invention is an improved reverse control or lock mechanism and relates to a control or lock for preventing a vehicle from running backward, when it is necessary to stop on an up grade 5 and which will not interfere on a resumption of forward movement.

The object of the invention is to improve generally upon such locks or mechanisms now in use and to provide a device of this character 10 which may be readily applied to the automobile, is thoroughly efficient in operation, and inexpensive to install and maintain.

The invention together with its objects and advantages will be best understood from a study 15 of the following description, taken in connection with the accompanying drawings wherein is illustrated a preferred embodiment of the invention.

Figure 1 is a top plan view of a portion of an 20 automobile illustrating the application of the invention thereto.

Figures 2, 3 and 4 are sectional views taken substantially on the lines 2—2, 3—3 and 4—4 respectively of Figure 1.

Figure 5 is a detail sectional view taken substantially on the line 5—5 of Figure 3.

Figure 6 is a perspective view of the locking plunger.

Figure 7 is a perspective view of the casing or 30 cylinder in which the locking plunger of Figure 6 operates.

Figure 8 is a perspective view of the cam shaft, and

Figure 9 is a sectional view through the shaft 35 with the cam mounted thereon and shown in elevation.

Referring to the drawings by reference numerals the casing or housing 10 is mounted on a pair of relatively spaced transverse bars 11 which are secured at the ends thereof to the chassis 40 bars 12 of the automobile. The housing or casing 10 is substantially circular and is provided on one side with a removable plate 13. Integral with the housing 10 and extending laterally 45 therefrom is a formation 14 having extending therethrough an opening 15 in which is snugly fitted a cylinder 16.

Mounted for reciprocation in the cylinder 16 is a locking plunger 17 the inner end of which 50 is engageable with the cam humps of a brake or lock cam 18 that is mounted on a shaft 19 journaled in suitable bearings 20, 21 provided respectively in one wall of the casing 10 and the cover plate 13.

As shown in Figure 8 intermediate its ends

the shaft 19 is provided with keys 22 that fit in ways suitably provided in the hub of the cam 18 as will be clear from a study of Figures 3 and 9. At one end of the keys 22 shaft 19 is provided with an integral collar 23 between which 60 and a removable collar 24 the cam 18 is retained on the shaft against longitudinal movement relative to the shaft. Also, as shown in Figure 5 the formations provided for the bearings 20, 21 and through which the shaft 19 extends are equipped with suitable packings 25 which surround the shaft as shown. At each end thereof the shaft 19 is squared or otherwise formed so as to be readily placed in driving engagement with the drive shaft 26 of the transmission. 70

The plunger 17 is normally urged inwardly for engagement with the humps of the cam 18 through the medium of a coil spring 27 that is disposed about the stem 28 of the plunger and 75 impinges at one end against the adjacent end of the plunger 17, and at a relatively opposite end against a plug 29 that is suitably anchored in the outer end of the cylinder 17. Suitably secured on the outer end of the plunger stem 28 80 is a rubber washer 30 which serves to limit the inward movement of the plunger 17 and the washer 30 being of rubber there will be no noticeable noise upon contact of the washer 30 with the plug 29. 85

For controlling operation of the plunger 17 there is provided a fork 31 that straddles the outer end of the plunger stem 28 between the washer 30 and a collar 32 provided on said stem. The shank portion of the fork 31 operates in a suitable bore provided therefor in the casing extension 14 and at its inner end has a pin and slot connection 33 with a lever 34 pivotally mounted within a vertical recess 35 provided therefore in the formation 14. A cap for the upper end of the 95 recess is provided on the lever 34 as indicated by the reference numeral 36; a suitable spring device 37 normally urging the cap 36 downwardly into closing position with respect to the recess 35. 100

The upper end of the lever 34 is connected with one end of a Bowden wire 38 that serves, as clearly shown in the drawings as a dash control for the manual manipulation of the plunger 17; the Bowden wire being provided with a suitable pull button 39 as shown. 105

To hold the plunger 17 in either released or projected position there is suitably provided in the formation 14 a spring pressed locking plunger or detent 40 that is engageable with notches pro- 110

vided on the shank of the fork 31 as shown in Figure 4.

The casing 10 is adapted to contain lubricant as shown in Figure 4, a filling opening for the casing being indicated by the reference numeral 41. A passage 42 for the lubricant leads through the formation 14 from the casing 10 to an aperture 43 provided in the cylinder 16, and obviously as the cam 18 is rotating certain of the lubricant 13 will be forced through the passage 42 and opening 43 against the side of the plunger 17 for lubricating purposes. Adjacent the stem equipped end thereof the plunger 17 is provided with a suitable packing 44.

15 The operation and utility of the device will be apparent from the following:

If desired the parts may be normally arranged as shown in Figure 4 with the plunger 17 arranged in the path of the humps on the cam 18, 20 and when in this position the plunger 17 and the teeth or humps of the cam 18 will prevent reverse rotation of the shaft 19 and likewise retrograde movement of the vehicle.

If at any time it is desired to release the 25 plunger 17 the operator by pulling on the knob 39 of the manual control for the device will cause the lever 34 to swing in a clockwise direction in Figure 4 thus moving the fork 31 to the left in Figure 4, and the plunger 17 in a corresponding direction against the action of spring 27 for drawing the free end of the plunger 17 out of the path of the teeth or humps of the cam 18 so that it is possible to permit the automobile to roll 30 backward. When the plunger 17 has been moved in this last noted direction the locking 35 plunger or detent 40 will move into engagement with the proper notch on the shank of the fork 31 and thus hold the parts in this position until such time as the control is manipulated for rocking the lever 34 in a reverse direction, when the 40 parts will then be returned to the position shown in Figure 4.

From the above it will be seen that the plunger 17 may be locked in either of its two positions, 45 and when locked in the position shown in Figure 4 will not interfere with the forward operation or movement of the vehicle, but at the same time will be in a position to coact with the humps or

teeth of the cam 18 to prevent retrograde movement of the automobile.

Having thus described my invention, what I claim as new is:

1. In a motor vehicle including a motor driven shaft, a casing, a cam having a plurality of cam teeth on its periphery, located in the casing and connected with the shaft, an extension at one side of the casing having a cylinder therein, one end of which is in communication with the interior of the casing, a plug for closing the other end of the casing, a plunger located in the cylinder and having one end adapted to be engaged by the cam teeth, a stem connected to the other end of the plunger and passing through the plug, a spring encircling the stem and having one end bearing against the plunger and the other end against the plug, spaced projections on the outer end of the stem, a yoke located between the projections and having a part slidably arranged in the extension, said part having a pair of spaced recesses therein, a detent carried by the extension for engaging either one of said recesses, a lever pivotally arranged in an opening in the extension and having one end pivotally connected 100 to said part of the yoke, operating means connected to the other end of the lever, a cap slidably arranged on the lever, spring means for holding the cap in position closing the lever opening.

2. In a motor vehicle including a motor driven shaft, a casing, a cam rotatably arranged in the casing and connected with the shaft and having cam teeth on its periphery, an extension on the casing having a cylinder therein, one end of which 110 is in communication with the interior of the casing, a spring pressed plunger in the cylinder for engaging the cam teeth, means for projecting and retracting the plunger, said casing containing lubricant and said extension having a passage 115 therein having one end in communication with the lower part of the casing and its other end in communication with the cylinder, whereby the rotation of the cam will force some of the lubricant from the casing through the passage into the 120 cylinder to lubricate the plunger.

OTIS F. RODGERS.
